MACHINE FOR BORING PISTONS

Ewald A. Arp, Minneapolis, Minn., assignor to
 Tobin-Arp Manufacturing Company, Minneapolis, Minn., a corporation of Minnesota

Application November 12, 1948, Serial No. 59,728

21 Claims. (Cl. 77—3)

1

This invention has relation to a machine which has been devised to be especially useful for boring the bearings of pistons, etc.

An object of the invention is to provide a machine for boring bearings, and particularly the bearings of pistons and articles or devices of like nature, which will be of novel and improved construction and designed to perform its intended service in novel and improved manner.

A further object is to provide a bearing boring machine wherein will be incorporated various desirable and improved features and characteristics novel both as individual entities of the machine and in combination with each other.

A further object is to provide a machine of the present character which will incorporate a novel and improved construction and arrangement for centering and alining with respect to each other bearings of articles, such as pistons, etc., to be bored and a boring bar with appropriate tool for operating on said bearings.

And a further object is to provide in the machine adjustable clamping units for supporting articles or devices bearings of which are to be bored which will be of simple, practical, efficient, novel and improved construction.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible as long as within the spirit of the invention and the scope of the claims which follow.

In the accompanying drawings forming a part of this specification,

Fig. 1 is a top plan view of a machine made according to the invention;

Fig. 2 is an enlarged fragmentary vertical sectional view, taken substantially on line 2—2 in Fig. 1, detailing features at an upper portion of the machine and disclosing an adjustable clamping unit of said machine partially in section and partially broken away;

Fig. 3 is an enlarged fragmentary vertical sectional view, taken substantially on line 3—3 in Fig. 1, detailing additional features at an upper portion of the machine;

Fig. 4 is an enlarged fragmentary vertical sectional view, taken on line 4—4 in Fig. 1;

Fig. 5 is an enlarged fragmentary vertical sec-

2

tional view, partially in elevation and partially broken away, and with parts omitted, of an adjustable clamping unit and associated parts of said machine, the portions of the view which are in elevation being shown as they would appear from the position of line 4—4 in Fig. 1;

Fig. 6 is a fragmentary vertical sectional view, taken substantially on line 6—6 in Fig. 1, detailing features at a lower portion of the machine;

Fig. 7 is a detail sectional view of parts at the right lower side of the disclosure of Fig. 6;

Fig. 8 is a detail sectional view of parts at the left lower side of the disclosure of said Fig. 6, and

Fig. 9 is a detail sectional view taken as on line 9—9 in Fig. 2.

The machine of the present invention has been set up on a frame also supporting mechanism, denoted A at the left in Fig. 1 of the drawings, forming no part of the invention which this application presents. In practical operation, the machine including the mechanism A and the machine herein illustrated and described have features in common in that they receive pressure fluid from a common source, are mounted upon a common frame work and are capable of being employed in connection with boring bar supporting units, disclosed at the right in said Fig. 1 and hereinafter described, also adapted to be mounted upon the common frame work. Stated otherwise,

Fig. 10 of the machine of the invention additionally supports mechanism A of a machine for accomplishing operations different from those herein set forth but capable of practical utilization on the same frame work in connection with devices or elements which are common to both machines. Said frame 10 is constituted as a rectilinear slab of rigid material, and can be supported in any suitable and convenient manner, as, for example, as part of a table, desirably so that the rectilinear slab will be horizontally disposed.

Spaced apart, parallel boring bar supporting units, indicated 11 and 12, respectively are situated upon the flat upper surface 13 of the frame 10 for slidably adjustable movement in direction toward and away from each other, and said supporting units 11 and 12 include self-alining bearings, represented 14 and 15, respectively, which can be of construction as disclosed in my pending application, Serial No. 44,442, for Self-Alining Bearing, filed August 16, 1948, adapted to be situated in alined relation in a single, desirably horizontal, plane to be capable of selectively receiving a locating rod or mandrel 16, as in Fig. 1, or a boring bar with cutting tool (not shown). The

50

supporting units 11 and 12 are keyed to the frame 10, as at 136, for slight rocking movement in a horizontal plane and fixed against movement in longitudinal direction.

The boring bar supporting unit 11 is constituted as an elongated rectilinear member disposed in perpendicular relation to the frame 10, as well as in perpendicular relation to a locating rod or mandrel, such as 16, or to a boring bar with cutting tool, when situated in the self-aligning bearings 14 and 15. A flat lower surface 17 of said boring bar supporting unit 11 rests upon the flat upper surface 13 of said frame 10 for slidable movement thereover toward and away from the boring bar supporting unit 12, and lower portions of the boring bar supporting unit 11 are cut away to provide spaced apart slots 18, contiguous with said flat lower surface 17 and parallel to a locating rod or mandrel or to a boring bar when in said self-aligning bearings 14 and 15, including upwardly facing shoulders 19 for a purpose to be made plain. Additionally, an upper portion of the boring bar supporting unit 11 includes spaced apart, horizontally disposed, longitudinally extending T-slots 20, contiguous with a flat interior surface 21 of said boring bar supporting unit 11 and perpendicular to a locating rod or mandrel or a boring bar when in the self-aligning bearings 14 and 15, as well as parallel with the frame 10, providing exteriorly facing shoulders 22 also for a purpose to be set forth. The flat interior surface 21 likewise is perpendicular to a locating rod or mandrel or a boring bar when in said self-aligning bearings 14 and 15 and to said frame 10.

The boring bar supporting unit 12 is constituted as an elongated rectilinear member disposed in perpendicular relation to the frame 10, as well as in perpendicular relation to a locating rod or mandrel, or to a boring bar, when situated in the self-aligning bearings 14 and 15. A flat lower surface 23 of said boring bar supporting unit 12 is in adjacent or contiguous relation to the flat upper surface 13 of said frame 10, and lower portions of the boring bar supporting unit 12 are cut away to provide spaced apart slots 24, contiguous with said flat lower surface 23 and parallel to a locating rod or mandrel, or to a boring bar, when in said self-aligning bearings 14 and 15, which contain supporting rollers 25 resting upon said flat upper surface 13 for rolling or sliding movement of the boring bar supporting unit 12 toward and away from the boring bar supporting unit 11. Also an upper portion of the boring bar supporting unit 12 includes spaced apart, horizontally disposed, longitudinally extending T-slots 26, contiguous with a flat interior surface 27 of said boring bar supporting unit 12 and perpendicular to a locating rod or mandrel or a boring bar when in the self-aligning bearings 14 and 15, as well as parallel with the frame 10, providing exteriorly facing shoulders 28 for the same purpose as are the exteriorly facing shoulders 22. The flat interior surface 27 is disposed in parallel relation to the flat interior surface 21.

The machine incorporates a pair of duplicate adjustable clamping units, each represented 29, and each clamping unit includes a clamping member 30.

The clamping members 30 are disposed in spaced, parallel relation to each other between and in perpendicular relation to the boring bar supporting units 11 and 12, and each clamping

member 30 is constituted as a housing which is of flat configuration in direction longitudinally of said boring bar supporting units and curvilinear at its upper portion and rectilinear at its lower portion. More explicitly stated, each clamping member or housing 30 includes a flat interior surface 31, oppositely disposed, parallel, lower rounded side surfaces 32, 32, a curvilinear upper side and top surface 33, and a hollowed out interior 34. The flat interior surface 31 is in perpendicular relation to the frame 10 and to the boring bar supporting units 11 and 12, the rounded side surfaces 32, 32 are in substantially parallel relation to the flat interior surfaces 21 and 27 of said boring bar supporting units, and said rounded side surfaces 32, 32 are provided by spaced apart, parallel side walls 35, 35, at the opposite ends of the hollowed out interior 34, in the instance of each clamping member or housing 30.

Each clamping member or housing 30 is assembled with end portions of the boring bar supporting units through the instrumentality of horizontally disposed locking elements, represented 36 and 37, respectively, for movement of said clamping members or housings longitudinally of said boring bar supporting units, toward and away from each other. The locking elements 36 and 37 of each clamping member are in aligned relation and are disposed in the hollowed out interior 34 of the corresponding clamping member in perpendicular relation to its oppositely disposed side walls 35, 35. More explicitly stated, each locking element 36 has its outer end portion snugly, slidably mounted in an opening through the side wall 35 of the corresponding housing adjacent the supporting unit 11 and its inner end portion snugly, slidably mounted in the adjacent end portion of an opening through a fitting 38 rigid with said corresponding housing disposed at the midlength of its hollowed out interior, and each locking element 37 has its outer end portion snugly, slidably mounted in an opening through the side wall 35 of the corresponding housing adjacent the supporting unit 12 and its inner end portion snugly, slidably mounted in the adjacent end portion of said opening through the fitting 38. The inner end portions of the locking elements 36 and 37 are hollow, and a compression coil spring 39 in said inner end portions, between cross pins 40, 40 rigid with said locking elements, normally urges the locking elements apart. A neck 41 with head 42 rigid with the outer end of each locking element 36 lies in the T-slot 20 at the corresponding end of the supporting unit 11, a neck 43 with head 44 rigid with the outer end of each locking element 37 lies in the T-slot 26 at the corresponding end of the supporting unit 12, said necks 41 and 43 with heads constitute means mounting each clamping member upon the supporting units for movement along their longitudinally extending T-slots, and the compression coil springs 39 normally retain the locking elements in position to permit the clamping members to be freely slideable along said supporting units toward and away from each other.

Each clamping member 30 suitably and conveniently supports a roller 45 at the midlength of its lower portion which rests upon the flat upper surface 13 of the frame 10 in perpendicular relation to the corresponding clamping member and in parallel relation to the supporting units 11 and 12, and each clamping mem-

ber 30 also suitably and conveniently supports mechanism, situated within its hollowed out interior 34, for causing the locking elements 36 and 37 to be actuated to cause the corresponding clamping member and the supporting units 11 and 12 to be gripped together, with the flat and rounded surfaces 21, 32 and 27, 32, respectively, engaged, thus to cause the clamping members and said supporting units to be locked together as a unitary structure.

A horizontal cylinder 46 rigid with each clamping member or housing 39, situated in its hollowed out interior 34 directly above and in spaced relation to its fitting 38, slidably supports spaced apart pistons 47, 47 in its opposite end portions. A space within each cylinder 46, between the corresponding pistons 47, 47, is denoted 48, and a port leading to said space 48 is indicated 49. Each piston 47 supports a neck 50, and packing surrounding the neck and engaged against the body of the corresponding piston, as well as against the interior surface of the corresponding cylinder 46, is represented 51. Fluid under pressure, applied in a manner to be set forth, within the spaces 48 of the cylinders 46 is adapted to cause the pistons 47, 47 to be forcibly moved apart, and said pistons will be free for movement toward each other upon relief of the fluid under pressure.

The outer ends of the pistons 47, 47 are engaged against the upper ends of longer arms 52, 52 of vertical actuating levers 53, 53 in the instance of each clamping member 30, intermediate portions of said vertical actuating levers are pivotally supported, as at 54, upon the corresponding clamping member, and lower end portions of shorter arms 55, 55 of the vertical actuating levers are engaged against surfaces of the cross pins 40, 40 of said corresponding clamping member which are opposite the compression coil spring 39. The construction and arrangement are such that the pistons 47, 47 will cause the longer arms 52, 52 of the actuating levers 53, 53 to be moved apart with movement apart of said pistons in response to application of fluid under pressure to the spaces 48 of the cylinders 46, thus to cause the shorter arms 55, 55 of said actuating levers and the locking elements 36, 37 to be moved toward each other, against resilient action of the compression coil springs 39, and the heads 42 and 44 upon said locking elements to be grasped against the shoulders 22 and 28, respectively, and said compression coil springs 39 will react upon relief of pressure in said cylinders 46 to cause the locking elements 36 and shorter arms of the actuating levers to be moved apart and said heads 42 and 44 to be released from said shoulders 22 and 28.

The boring bar supporting unit 11 is adapted to be locked down against the flat upper surface 13 of the frame 10, thus to anchor said clamping members and supporting units to said frame, through the instrumentality of vertically disposed locking elements 56 slidably mounted, as at 57, in the frame 10. The upper end portion of each locking element 56 is disposed above the flat upper surface 13 of said frame 10 in a slot 18, and a compression coil spring 58, upon each locking element 56 between a collar 59 thereon and said flat upper surface 13, normally urges the corresponding locking element 56 upwardly. A neck 60 with head 61 rigid with the upper end of each locking element 56 lies in the slot 18 at the corresponding end of the supporting unit 11 with said head 61 above and said neck

60 between upwardly facing shoulders 19 of said supporting unit 11, and said compression coil springs 58 normally retain the locking elements 56 in position to permit the supporting unit 11 to be released from the flat upper surface 13 of the frame 10.

A vertical cylinder 62, in surrounding relation to the lower end portion of each vertically disposed locking element 56 and rigid with the lower surface of the frame 10, slidably supports a piston 63 fixed, as at 64, upon said vertically disposed locking element. A space within each cylinder 62, above the corresponding piston 63, is denoted 65, and a port leading to said space 65 is represented 66. Each piston 63 supports a neck 67, and packing surrounding the neck and engaged against the body of the corresponding piston, as well as against the interior surface of the corresponding cylinder 62, is represented 68. Fluid under pressure, applied through a flexible hose 69, within the spaces 65 of the cylinders 62 is adapted to cause the pistons 63 to be forcibly moved downwardly, and said pistons will be free for upward movement upon relief of the fluid under pressure. The construction and arrangement are such that the heads 61 will be moved downwardly with downward movement of the pistons 63, against resilient action of the compression coil springs 58, to be grasped against the shoulders 19, and said compression coil springs 58 will react upon relief of pressure in said cylinders 62 to cause the heads 61 of the locking elements to be released from said shoulders 19.

Each adjustable clamping unit 29 includes a pushrod 70, of construction and assembled with the clamping member 30 of the corresponding adjustable clamping unit in a manner to be described, and an operating lever 71, of construction and assembled with the frame 10 and the pushrod 70 of the corresponding adjustable clamping unit in a manner also to be described. The pushrod 70 of each adjustable clamping unit is assembled with the clamping member 30, is disposed centrally of the flat interior surface 31 and extends exteriorly of said clamping member in perpendicular relation thereto, as well as in parallel relation to the frame 10, and the operating levers 71 of the adjustable clamping units 29, 29 are disposed at opposite sides of said frame. More explicitly stated, intermediate portions of said operating levers 71 are pivotally mounted, as at 72, upon opposite side portions of the frame 10 for swinging movement of the operating levers in a vertical plane parallel with the supporting units 11 and 12 and perpendicular to the clamping members 30, 30, upper arms 73 of said operating levers extend upwardly from the pivotal supports 72, and lower arms 74 of the operating levers extend downwardly from said pivotal supports. The upper end portions of the upper arms 73 are rotatably assembled with the pushrods 70 in a manner to be made clear. The lower ends of the lower arms 74 are adapted to be forcibly moved apart, in response to application of fluid under pressure, to cause the clamping members 30 to be forcibly moved toward each other, and moved toward each other, upon relief of pressure, to allow said clamping members to be moved apart.

Mechanism for forcibly moving the lower arms 74, 74 of the operating levers 71 apart includes a horizontal cylinder 75 below the frame 10 and pivotally connected, as at 76, with the lower end of one of the lower arms 74, the one at the right in Figs. 6 and 7, and a horizontal connecting rod

aligned with the horizontal cylinder 75 and pivotally connected, as at 78, with the lower end of the other of said lower arms 74, the one at the left in Figs. 6 and 8. More explicitly stated, the horizontal cylinder 75 is closed at its outer end by a cap member 79 supporting spaced apart ears 80 to which the lower end of the lower arm 74 at the same side of the frame 10 is pivotally connected, and said horizontal cylinder 75 is closed at its inner end by a cap member 81 which includes an annular opening 82 in which a sleeve 83 is rigidly supported. Said sleeve 83 extends inwardly from the cap member 81 in spaced surrounding relation to the connecting rod 77, and the outer end of the sleeve is closed by a head 84 through which said connecting rod snugly passes and is slidably arranged. One end portion of the connecting rod 77 is rigidly secured, as at 85, to a piston 86 slidably arranged in the horizontal cylinder 75, and a port 87 contiguous with a space 88 of said horizontal cylinder 75 at the side of the piston 86 opposite said connecting rod 77 is for application of fluid under pressure to said space. The piston 86 supports a neck 89, and packing surrounding the neck and engaged against the body of the piston, as well as against the interior surface of the cylinder 75, is indicated 90. The other end portion of the connecting rod 77 adjustably supports, as at 91, an attachment piece 92, and said attachment piece is pivotally connected to the lower end of the lower arm 74 at the corresponding side of said frame 10. A compression coil spring 93, on the connecting rod 77 and in the cylinder 75 and the sleeve 83, has one of its ends engaged against the piston 86 and its other end engaged against the head 84 normally to urge said connecting rod inwardly of said cylinder thus to urge the lower arms 74, 74 of the operating levers 71, 71 toward and the upper arms 73, 73 of said operating levers away from each other. It will be apparent that fluid under pressure applied to the space 88 of the cylinder 75 will cause the piston 86 and the connecting rod 77 to be moved outwardly of said cylinder thus to cause the lower arms 74 of the operating levers 71 to be moved away from each other and the upper arms 73 of said operating levers to be moved toward each other, and that the compression coil spring 93 will cause said piston and connecting rod to be moved inwardly of the cylinder upon relief of pressure thus to cause said lower arms 74 to be moved toward each other and said upper arms 73 to be moved away from each other.

Each pushrod 70 includes an external thread 94, and an actuator nut 95 is adjustably situated upon each external thread 94. Each actuator nut 95 is of cylindrical configuration and each pushrod 70 passes transversely through the mid-length of its corresponding actuator nut in such manner that the actuator nuts can be disposed with their longitudinal axes in a horizontal plane.

The upper end portion of the upper arm 73 of each operating lever 71 is cut away to provide spaced apart, upwardly opening concavities 96 aligned in direction parallelly of the clamping members 30, 30 adapted selectively to receive a corresponding pushrod 70, and inwardly of said concavities said upper end portion of each upper arm 73 provides a downwardly and inwardly extending curvilinear surface 97 and a horizontal surface 98 against and upon which the corresponding actuator nut 95 is adapted to rest, as disclosed in Figs. 1 and 2 of the drawings.

The obvious purpose of the several different aligned concavities 96 is for setting pushrods such as 70, 70 closer to or farther from the boring bar supporting unit 11, depending upon the size 5 of a piston or other device or article the bearing of which is to be bored. With adjustment of said pushrods 70, 70 relative to said supporting unit 11, the supporting unit 12 will be adjusted to correspond, closer to or farther from 10 the supporting unit 11, as the case may be.

Concavities 96 in the upper arms 73 of operating levers 71 at opposite sides, respectively, of the frame 10 are in alignment in direction transversely of said frame and parallelly of the 15 supporting units 11 and 12, and the construction and arrangement will be such that when said upper arms 73 are forcibly moved toward each other, the pushrods 70 and the clamping members 30, 30 also will be forcibly moved toward each other in direction longitudinally of 20 said pushrods, through the instrumentality of the upper end portions of the operating levers 71 and the actuator nuts 95. The construction and arrangement also will be such that when the 25 lower arms 74 of the operating levers 71 are moved toward each other to cause the upper arms 73 of said operating levers to be moved apart, the pushrods and said clamping members will be free to have movement in direction away 30 from each other.

The outer end of each pushrod 70 supports an actuator piece 99. Vertical plates 100 upon the interior surfaces of the upper arms 73, 73 of the operating levers 71 include upper extensions 101, each having concavities 102 aligned with concavities 96, for precluding outward swinging movement of said upper arms to position clear of the actuator nuts 95. The pushrods 70 lie in the concavities 102, and the upper extensions 101 preclude removal of said actuator nuts 95 off of the horizontal surfaces 98 with outward swinging movement of said upper arms 73, 73. Instead, said upper extensions 101 will engage the actuator nuts 95 with outward swinging 45 movement of the upper arms 73, 73 and cause the pushrods 70 and the clamping members 30 to be moved away from each other.

Rubber skirts secured to the vertical plates 100 and overlapping the opposite side marginal edge 50 portions of the frame 10 are denoted 103.

The end portion of each pushrod 70 opposite the actuator piece 99 includes a reduced cylindrical portion 104 situated within the clamping member 30 of the corresponding clamping unit 29 and fixedly supporting an interior collar 105 engaged against an annular shoulder 106 of the pushrod. An external surface 107 of each interior collar 105 is of conical configuration and tapers in direction from the corresponding 55 clamping member toward the corresponding pushrod. An exterior collar 108 is fixed, as at 109, to a cylindrical internal surface of the corresponding clamping member bounding a chamber 110 which said corresponding clamping member provides. An internal surface 111 of each exterior collar 108 is of conical configuration and tapers in direction from the corresponding clamping member toward the corresponding pushrod, and the external surface 107 of each 60 interior collar 105 is slidably fitted against the internal surface 111 of each exterior collar 108. A lock plate 112 engages the exterior collar 108, and a retainer plate 113, secured against the adjacent surface of the corresponding clamping member as at 114, secures each lock plate in its 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 intended position. The construction and arrangement are such that the interior collar 105 on each pushrod 70 will rock in the corresponding exterior collar 108 in a horizontal plane but will be fixed in said corresponding exterior collar against rocking movement in a vertical plane.

Each pushrod 70 is hollow, as indicated at 115, and a connector 116 for fluid under pressure opens to the hollow interior of each pushrod, as denoted at 117.

A stub end 118 in each chamber 110 is rigidly fitted, as at 119, into the adjacent open end of the corresponding pushrod 70, and a port 120, contiguous with the interior of said corresponding pushrod, through each stub end, is open, as at 121, to an external surface of the stub end in remote relation to the corresponding pushrod.

Each chamber 110 houses a clamping plug 122 which is fixed in the corresponding clamping member 30 and is disposed in spaced, adjacent relation to the end of the corresponding stub end 118 opposite the corresponding pushrod 70. A rounded closure wall 123 of each clamping plug 122 protrudes beyond the flat interior surface 31 of the corresponding clamping member 30, and the body of each clamping plug is hollow and is fitted, as denoted at 124, in said corresponding clamping member in spaced, surrounding relation to the corresponding stub end 118 and pushrod 70. A compression coil spring 125, within each chamber 110 upon the corresponding stub end and pushrod, has one of its ends engaged against the corresponding interior collar 105 and its other end engaged against the corresponding clamping plug 122 normally to urge said interior collar inwardly of the corresponding clamping member 30. An internal annular shoulder 126 of each clamping member 30 is engaged by an external annular shoulder 127 upon the corresponding clamping plug 122, and each compression coil spring 125 normally retains the corresponding interior collar 105 seated in its corresponding exterior collar 108, with the outer part of the corresponding stub end 118 in spaced, adjacent relation to the corresponding clamping plug, as disclosed in Fig. 2 of the drawings. A port 128 in each clamping plug 122 affords passage for fluid under pressure from the port 121 of the corresponding clamping unit to the port 49 leading to the corresponding chamber 48. Packing 129, about each stub end 118 and engaged with an internal surface of the corresponding clamping plug 122 provides a compartment 130 within said corresponding clamping plug surrounding the corresponding stub end 118 and isolates the ports 121 and 128 from the corresponding chamber 110.

In the accomplishment of practical operation of the machine, the boring bar supporting units 11 and 12 will be set up on the frame 10 in spaced relation to each other a distance apart slightly greater than, or approximately equal to, the distance apart of the rounded side surfaces 32, 32 of each clamping member 30, and the supporting unit 11 will be fastened down on the frame 10 in the manner as hereinbefore set forth. A device or article a bearing of which is to be reborod, such as a piston 135, disclosed in Fig. 1 of the drawings, will be placed between said supporting units, and a locating rod or mandrel, such as 16, will be inserted in and through the self-aligning bearing 14, said device, article or piston and the self-aligning bearing 15, as in said Fig. 1. Thereafter, the clamping units 29 will be actuated to cause the clamping members 30 to grasp oppositely disposed surfaces of the device, article or piston.

Supposing the device or article a bearing of which is to be reborod to be a piston, said piston will be situated so that its longitudinal axis is disposed in a plane parallel to the frame 10 with the closed end of the piston adjacent one of the clamping members 30 and the open end of said piston adjacent the other of said clamping members 30, and with the piston so situated, fluid under pressure will be applied to the space 88 of the horizontal cylinder 75. The lower arms 74, 74 of the operating levers 71, 71 will be forcibly moved away from each other in response to application of pressure fluid to said space 88 thus to cause the upper arms 73, 73 of said operating levers, and hence the pushrods 70, 70 and the clamping members 30, 30, to be forcibly moved toward each other. The flat interior surface 31 of the clamping member 30 which the open end of the piston is adjacent will engage said open end, and the rounded interior surface of the closure wall 123 which the closed end of the piston is adjacent will engage a central portion of said closed end.

The exterior collars 108 will engage the interior collars 105 in such manner as to retain the clamping members 30 fixed in a vertical plane but free to rock in a horizontal plane while the clamping plugs 122 and the flat interior surfaces 31 become engaged with oppositely disposed surfaces of a device or article such as the piston 135. Upon application of force to the clamping members 30, tending to move one of the clamping plugs and one of the clamping members, inward movement of said clamping members will be arrested by the device, article or piston. Instead, the pushrods 70 with stub ends 118 move inwardly of the clamping members 30, against resilient action of the compression coil springs 125, until said stub ends are engaged against the clamping plugs 122 and the interior collars 105 are released from the exterior collars 108 and situated at the side thereof adjacent said clamping plugs. The construction and arrangement are such that when said interior collars are released from said exterior collars, the clamping plugs 122 and the clamping members 30 will be supported upon annular shoulders of the stud ends 118 just inwardly of the packings 129 for universal rocking movement. Upon the application of force to the clamping members 30 and the clamping plugs 122 causing them to be pressed against a device, article or piston, said clamping members will be capable of rocking in universal direction relative to said device, article or piston with the result that the clamping members and clamping plugs will exert retaining pressure against opposed surfaces of the device, article or piston in direction longitudinally thereof and apply no force tending to impart rocking movement to said device, article or piston. The clamping members 30 will be held substantially vertical by cooperation of the interior and exterior collars 105 and 108 when engaged and the annular shoulders disposed inwardly of the packings 129. The compression coil springs 125 will be of sufficient strength to level the work, such as a piston, to be bored. As will be apparent from Fig. 9, the internal surfaces 111 will be in clearing relation to the external surfaces 107 at their opposite sides and engaged with said external surfaces at their tops and bottoms when the internal and external collars 105 and 108 are in engagement so that the clamping members 30 can rock in a horizontal plane relative to the work or piston. At the same time, said internal

and external collars cooperate to maintain the clamping members in vertical position while the work or piston rocks in a vertical plane, about the locating rod or mandrel 16, relative to said clamping members. When the pushrods 70 move the clamping members into engagement with a piston, the piston is rotated on its locating rod or mandrel to become engaged either by a flat interior surface 31 or a rounded closure wall 123, as the case may be. Upon removal of the interior collars 105 from the exterior collars 108, the annular shoulders disposed inwardly of the packings 129 maintain the clamping plugs 122, and hence the clamping members 30, snugly supported upon the stub ends 118 but permit said stub ends to slide within said clamping plugs. The outer portions of the stub ends are somewhat rounded, and the construction and arrangement as illustrated and described is provision for universal rocking movement of the clamping members when the interior and exterior collars 105 and 108 are disengaged. Thus, said clamping members are adapted to take their final alignment from the piston.

It will be apparent that the clamping members and clamping plugs will be actuated in response to fluid under pressure to cause the opposite ends of devices or articles to be rebored to be engaged with equal pressure and so that there will be no distorting pressure applied to the locating element or rod.

The supporting units 11 and 12 will be grasped to the clamping members 30, 30 after said clamping members have been gripped against oppositely disposed surfaces of a device or article a bearing of which is to be rebored. Fluid under pressure for actuating the pistons 47, 47 is applied to the space 48 of the cylinders 46 by way of the connectors 116, the hollow interiors of the pushrods 70, the ports 120 and 121 in the stub ends 118, the compartments 130, the ports 128 in the clamping plugs 122, the chambers 110 and the ports 49. The self-aligning bearings 14 and 15 will permit rocking movement of the supporting units 11 and 12 in universal direction relative to said self-aligning bearings during the operation of locking said supporting units to said clamping members, so that securing the supporting units up against the clamping members will have no tendency toward displacing the set relation of said clamping members with respect to a retained device, article or piston. And, too, the supporting unit 12 is pulled toward the supporting unit 11 in direction longitudinally of the locating rod or mandrel so that there is no tendency toward disalignment.

The locking elements 36 and 37 will be actuated in response to fluid under pressure to cause the supporting units 11 and 12 to be engaged against the clamping members 30, 30 with equal pressure.

Pressure of fluid in the spaces 48 of the cylinders 46 and in the space 88 of the cylinder 75 will be relieved when a device or article is to be removed from the machine, and another device or article the bearing of which is to be rebored can be located in the machine by repetition of the operations hereinbefore described.

In an instance when a device, article or piston having a bearing to be rebored is of shape other than flat at one of its ends, as for instance when a piston has an irregularly shaped closed end, the machine can incorporate special means for supporting the device, article or piston. As disclosed, one of the clamping members 30 detachably sup-

ports, as at 131, a disc element 132 disposed forwardly of and in spaced relation to the flat interior surface 31. The central portion of said disc element is cut away to be in clearing relation to the corresponding clamping plug 122, and the body of the disc element retains, through the instrumentality of clips 134, spacing screws 133. The heads of the spacing screws are situated between the disc element and the clamping member and the bodies of said spacing screws terminate in unequally spaced relation to said clamping member. In an instance when employed, the spacing screws 133 will engage the device, article or piston to be rebored, in lieu of the flat interior surface 31.

It will be understood of course that the locating rod or mandrel, such as 16, will be removed from a device or article having a bearing to be rebored after said device or article is set up in the machine, and a boring bar with appropriate cutting tool will be set up in the bearings of the supporting units 11 and 12 and actuated to accomplish a reboring operation upon the bearing of the device or article.

What is claimed is:

1. In a machine for centering and alining with respect to each other the bearing of an article to be rebored and a boring bar with appropriate tool for reboring said bearing, a frame, spaced apart supporting units mounted on said frame for movement toward and away from each other, alined bearings upon said supporting units, respectively, adapted to removably receive a boring bar locating element for insertion through the bearing of said article while situated between said supporting units, spaced apart clamping units between and slidably assembled with said supporting units mounted for movement toward and away from each other in direction transversely of the direction in which said supporting units are capable of movement, means for actuating said clamping units into releasably engaged relation with oppositely disposed surfaces of said article while the article is upon said locating element in spaced relation to said supporting units, and means for releasably securing said supporting units and clamping units in fixed relation to each other with the clamping units engaged against said oppositely disposed surfaces of said article and the supporting units engaged against opposed surfaces of each of the clamping units.

2. In a machine for centering and alining with respect to each other the bearing of an article to be rebored and a boring bar with appropriate tool for reboring said bearing, a frame, spaced apart supporting units mounted on said frame for movement toward and away from each other, alined bearings upon said supporting units, respectively, adapted to removably receive a boring bar locating element for insertion through the bearing of said article while situated between said supporting units, spaced apart clamping units between and slidably assembled with said supporting units mounted for movement toward and away from each other in direction transversely of the direction in which said supporting units are capable of movement, means for actuating said clamping units into releasably engaged relation with oppositely disposed surfaces of said article while the article is upon said locating element in spaced relation to said supporting units, means for releasably securing said supporting units and clamping units in fixed relation to each other with the clamping units engaged against said oppositely disposed surfaces of said article and the supporting units engaged against opposed surfaces of each of the clamping units.

article and the supporting units engaged against opposed surfaces of each of the clamping units, and means for releasably securing said supporting units in fixed relation to said frame.

3. In a machine for centering and alining with respect to each other the bearing of an article to be rebored and a boring bar with appropriate tool for reboring said bearing, a frame, spaced apart, parallel supporting units mounted on said frame for movement toward and away from each other, alined self-alining bearings upon said supporting units, respectively, adapted to removably receive a boring bar locating element for insertion through the bearing of said article while situated between said supporting units, spaced apart, parallel clamping members between, slidably assembled with and perpendicular to said supporting units mounted for movement toward and away from each other in direction transversely of the direction in which said supporting units are capable of movement, means for actuating said clamping members into releasably engaged relation with oppositely disposed surfaces of said article while the article is upon said locating element in spaced relation to said supporting units, and means for releasably securing said supporting units and clamping members in fixed relation to each other with the clamping members engaged against said oppositely disposed surfaces of said article and the supporting units engaged against opposed surfaces of each of said clamping members.

4. In a machine for centering and alining with respect to each other the bearing of an article to be rebored and a boring bar with appropriate tool for reboring said bearing, a frame, spaced apart, parallel supporting units mounted on said frame for movement toward and away from each other, alined self-alining bearings upon said supporting units, respectively, adapted to removably receive a boring bar locating element for insertion through the bearing of said article while situated between said supporting units, spaced apart, parallel clamping members between, slidably assembled with and perpendicular to said supporting units mounted for universal rocking movement and for movement toward and away from each other in direction transversely of the direction in which said supporting units are capable of movement, means for actuating said clamping members into releasably engaged relation with oppositely disposed surfaces of said article while the article is upon said locating element in spaced relation to said supporting units, and means for releasably securing said supporting units and clamping members in fixed relation to each other with the supporting units engaged against opposed surfaces of each of the clamping members.

5. In a machine for centering and alining with respect to each other the bearing of an article to be rebored and a boring bar with appropriate tool for reboring said bearing, a frame, spaced apart, parallel supporting units mounted on said frame for movement toward and away from each other, alined self-alining bearings upon said supporting units, respectively, adapted to removably receive a boring bar locating element for insertion through the bearing of said article while situated between said supporting units, spaced apart, parallel clamping members between and perpendicular to said supporting units mounted upon the supporting units for movement toward and away from each other in direction transversely of the direction in which said supporting units are capable of movement, means for actu-

ating said clamping members into releasably engaged relation with oppositely disposed surfaces of said article while the article is upon said locating element in spaced relation to said supporting units, and means for releasably securing said supporting units and clamping members in fixed relation to each other with the clamping members engaged against said oppositely disposed surfaces of said article and the supporting units engaged against oppositely disposed surfaces of each of said clamping members.

6. In a machine for centering and alining with respect to each other the bearing of an article to be rebored and a boring bar with appropriate tool for reboring said bearing, a frame, spaced apart, parallel supporting units mounted on said frame for movement toward and away from each other, alined self-alining bearings upon said supporting units, respectively, adapted to removably receive a boring bar locating element for insertion through the bearing of said article while situated between said supporting units, spaced apart, parallel clamping members between and perpendicular to said supporting units mounted for universal rocking movement and for movement toward and away from each other in direction transversely of the direction in which said supporting units are capable of movement, means for actuating said clamping members into releasably engaged relation with oppositely disposed surfaces of said article while the article is upon said locating element in spaced relation to said supporting units, means for releasably securing said supporting units and clamping members in fixed relation to each other with the clamping members engaged against said oppositely disposed surfaces of said article and the supporting units engaged against oppositely disposed surfaces of said clamping members, and means for releasably securing at least one of each of said supporting units in fixed relation to said frame.

7. In a machine for centering and alining with respect to each other the bearing of an article to be rebored and a boring bar with appropriate tool for reboring said bearing, a frame, spaced apart supporting units mounted on said frame for movement toward and away from each other, alined bearings upon said supporting units, respectively, adapted to removably receive a boring bar locating element for insertion through the bearing of said article while situated between said supporting units, spaced apart clamping units between said supporting units mounted for movement toward and away from each other in direction transversely of the direction in which said supporting units are capable of movement, hydraulic means for actuating said clamping units into releasably engaged relation with oppositely disposed surfaces of said article while the article is upon said locating element in spaced relation to said supporting units, hydraulic means for releasably securing said supporting units and clamping units in fixed relation to each other with the supporting units engaged against opposed surfaces of each of the clamping units, and means for releasably securing said supporting units and clamping units to said frame.

8. In a machine for centering and alining with respect to each other the bearing of an article to be rebored and a boring bar with appropriate tool for reboring said bearing, a frame, spaced apart, parallel supporting units mounted on said frame for movement toward and away from each other, alined self-alining bearings upon said supporting units, respectively, adapted to removably receive a boring bar locating element for inser-

tion through the bearing of said article while situated between said supporting units, spaced apart, parallel clamping members between and perpendicular to said supporting units mounted for universal rocking movement and for movement toward and away from each other in direction transversely of the direction in which said supporting units are capable of movement, hydraulic means for actuating said clamping members into releasably engaged relation with oppositely disposed surfaces of said article while the article is upon said locating element in spaced relation to said supporting units, hydraulic means for releasably securing said supporting units and clamping members in fixed relation to each other with the supporting units engaged against opposed surfaces of each of the clamping members, and hydraulic means for releasably securing said supporting units and clamping members in fixed relation to said frame.

9. In a machine for centering and alining with respect to each other the bearing of an article to be rebored and a boring bar with appropriate tool for reboring said bearing, a frame, spaced apart supporting units mounted on said frame for movement toward and away from each other, alined self-alining bearings upon said supporting units, respectively, adapted to removably receive a boring bar locating element for insertion through the bearing of said article while situated between said supporting units, spaced apart clamping units between and upon said supporting units mounted for universal rocking movement and for movement toward and away from each other in direction transversely of the direction in which said supporting units are capable of movement, means for actuating said clamping units toward each other into releasably engaged relation with oppositely disposed surfaces of said article while the article is upon said locating element in spaced relation to said frame and said supporting units, and means for releasably securing said supporting units and clamping units in fixed relation to each other with the supporting units engaged against opposed surfaces of each of the clamping units.

10. In a machine for centering and alining with respect to each other the bearing of an article to be rebored and a boring bar with appropriate tool for reboring said bearing, a frame, spaced apart supporting units mounted on said frame for movement toward and away from each other, alined self-alining bearings upon said supporting units, respectively, adapted to removably receive a boring bar locating element for insertion through the bearing of said article while situated between said supporting units, spaced apart clamping units between and upon said supporting units mounted for universal rocking movement and for movement toward and away from each other in direction transversely of the direction in which said supporting units are capable of movement, hydraulic means for actuating said clamping units toward each other into releasably engaged relation with oppositely disposed surfaces of said article while the article is upon said locating element in spaced relation to said frame and said supporting units, hydraulic means for releasably securing said supporting units and clamping units in fixed relation to each other with the supporting units engaged against opposed surfaces of each of the clamping units, and means for anchoring said supporting units and clamping units to said frame.

11. In a machine of the character described, a frame, supporting units mounted on said frame

for movement toward and away from each other, a clamping member between said supporting units, locking elements upon said clamping member in opposed relation to each other and having outer portions thereof situated at opposite sides of the clamping member and slidably disposed in longitudinally extending slots in said supporting units, resilient means normally retaining said locking elements in released engagement relative to said supporting units, and means for actuating said locking elements against force of said resilient means to cause said supporting units to be fixedly secured to and against said clamping member.

12. In a machine of the character described, a frame, supporting units mounted on said frame for movement toward and away from each other and having longitudinally extending T-slots, a clamping member between said supporting units, locking elements in alined relation upon said clamping member and having outer portions thereof slidably disposed in said longitudinally extending T-slots, resilient means between and normally urging said locking elements apart and in released engagement relative to said supporting units, a cylinder upon said clamping member, spaced apart pistons in said cylinder, and actuating levers having intermediate portions thereof pivoted upon said clamping member, first end portions thereof engaged with said locking elements and second end portions thereof engaged against outer end portions of said pistons, there being a space in said cylinder for receiving fluid under pressure adapted to cause said pistons to be forcibly moved apart thus to operate said actuating levers to forcibly move said locking elements toward each other to cause said supporting units to be fixedly secured to and against said clamping member.

13. In a machine of the character described, a clamping member having a chamber, a pushrod secured to said clamping member and having an internal passageway contiguous with said chamber, a cylinder upon said clamping member, and spaced apart pistons in said cylinder, there being a space in said cylinder for receiving fluid under pressure adapted to cause said pistons to be forcibly moved apart, and there being a port between said chamber and space for passage of fluid under pressure from the internal passageway of said pushrod and said chamber into said space.

14. In a machine of the character described, clamping members in spaced apart, alined relation having interior surfaces situated in opposed, substantially parallel relation, alined pushrods extending exteriorly from said clamping members, respectively, at the exterior sides thereof, clamping plugs in said clamping members at the interior sides thereof in overlapping relation to said pushrods and constituting means for mounting the clamping members upon the pushrods for universal rocking movement, means each constituted as an exterior and an interior collar securing said clamping members upon said pushrods for rocking movement of the clamping members in a horizontal plane and precluding relative movement of the pushrods and said clamping members in a vertical plane, and a resilient member normally urging the exterior and interior collars of each of said clamping members into engaged relation, movement of said pushrods in longitudinal direction toward said clamping members being adapted to release said interior collars from said exterior collars against the action of said resilient members thus to cause the clamping plugs to constitute means mounting

the clamping members upon the pushrods for universal rocking movement.

15. In a machine of the character described, a frame, spaced apart supporting units mounted on said frame for movement toward and away from each other, alined bearings upon said supporting units to removably receive a boring bar locating element for insertion through the bearing of an article to be bored, spaced apart clamping units between said supporting units mounted for movement toward and away from each other in direction transversely of the direction in which said supporting units are capable of movement to be releasably engaged against opposed surfaces of said article while upon said locating element in spaced relation to said supporting units, and means assembled directly with the supporting units and clamping units for releasably securing said supporting units against opposite surfaces of each of said clamping units while engaged against said article and in fixed relation to said frame.

16. The combination as specified in claim 15 wherein said clamping units are mounted for universal rocking movement.

17. The combination as specified in claim 15 wherein said clamping units are mounted upon said supporting units for universal rocking movement.

18. The combination as specified in claim 15 wherein said means includes locking elements upon each of said clamping units disposed in slots in each of said supporting units.

19. In a machine of the character described, a frame, spaced apart operating levers having intermediate portions thereof mounted on said frame for swinging movement of first and second arms, respectively, of said operating levers toward and away from each other, means for forcibly moving the second arms of said operating levers in direction away from each other thus to move the first arms of said operating levers toward each other, alined pushrods having intermediate portions thereof assembled with the first arms of the operating levers for longitudinal adjustment of the pushrods in the plane of swinging movement of said first arms and for rocking movement of said pushrods, and spaced clamping

members supported upon said pushrods in alined relation therewith and disposed between the first arms of said operating levers.

20. The combination as specified in claim 19, 5 means securing each of said pushrods to its corresponding clamping member, and means for accomplishing longitudinal adjustment of said pushrods constituted as an external thread on each pushrod and an actuator nut on each external thread rotatably assembled with one of said first arms.

21. In a machine of the character described, a frame, supporting units mounted on said frame for movement toward and away from each other, a clamping member between said supporting units, locking elements upon said clamping member in opposed relation to each other and having outer portions thereof situated at opposite sides of the clamping member and disposed in longitudinally extending slots in said supporting units, resilient means normally retaining said locking elements in released engagement relative to said supporting units, and means for actuating said locking elements toward said clamping member against force of said resilient means to cause the supporting units to be fixedly secured against opposed surfaces of the clamping member.
